(57) **CLAIM**

An ornamental design for a magnifier, as shown and
described.

DESCRIPTION

FIG. 1 is an isometric view showing the right side, top, and
front of our design of a magnifier.

FIG. 2 is a left side elevational view thereof.

FIG. 3 is a front elevational view thereof.

FIG. 4 is a right side elevational view thereof.

FIG. 5 is a rear elevational view thereof.

FIG. 6 is a top plan view thereof.

FIG. 7 is a bottom view thereof.

FIG. 8 is an isometric view showing the left side, top, and
front thereof.

FIG. 9 is an isometric view showing the left side, bottom,
and front thereof.

FIG. 10 is an isometric view showing the right side, bottom,
and front thereof.

FIG. 11 is an isometric view showing the right side, top, and
front the magnifier of FIG. 1 shown in alternative position.

FIG. 12 is a left side elevational view thereof.

FIG. 13 is a front elevational view thereof.

FIG. 14 is a right side elevational view thereof.

FIG. 15 is a rear elevational view thereof.

FIG. 16 is a top plan view thereof.

FIG. 17 is a bottom view thereof.

FIG. 18 is an isometric view showing the left side, top, and
front thereof.

FIG. 19 is an isometric view showing the left side, bottom,
and front of the magnifier of FIG. 1 shown in a second
alternative position; and,

FIG. 20 is a front elevational view thereof.

The broken lines depict portions of the magnifier that form
no part of the claimed design.

1 Claim, 20 Drawing Sheets
